UNITED STATES PATENT OFFICE.

ROBERT A. PHILP, OF PORTLAND, OREGON.

BURGLAR-ALARM.

1,196,394.

Specification of Letters Patent. Patented Aug. 29, 1916.

Application filed December 13, 1913. Serial No. 806,516.

To all whom it may concern:

Be it known that I, ROBERT A. PHILP, a citizen of the United States, residing at Portland, in the county of Multnomah and State of Oregon, have invented certain new and useful Improvements in Burglar-Alarms; and I do hereby declare the following to be a full, clear, and exact description of the invention, such as will enable others skilled in the art to which it appertains to make and use the same.

This invention comprehends improvements in burglar alarms and relates more particularly to those which are especially adapted for use in conjunction with a door, the opening of the door causing the alarm to sound.

One of the objects of the invention is to provide a very simply constructed burglar alarm including a main supporting plate formed with a spring tongue, an alarm mechanism mounted on said plate and means for holding the plate against a door so that an attempt to open the door will result in actuating the spring tongue to set the alarm mechanism into operation.

Another object of the invention is to provide an alarm of this nature consisting of a minimum number of parts and so constructed as to fold into a very compact form, whereby the practicability and usefulness of the article is greatly enhanced since it may be packed in a very small space to facilitate transportation.

The invention also aims to generally improve alarms of this nature to render them more efficient, reliable and commercially desirable.

With these and other objects in view as will become more apparent as the description proceeds, the invention consists in certain novel features of construction, combination and arrangement of parts as will be hereinafter more fully described and claimed.

For a complete understanding of my invention reference is to be had to the following description and accompanying drawings, in which—

Figure 1 is a vertical sectional view, showing the alarm in operative position against a door, Fig. 2 is a top plan view of the burglar alarm, showing the spring tongue locked in operative position, Fig. 3 is a fragmentary top plan view, showing the spring tongue in its normal inoperative po-

sition, and Fig. 4 is a fragmentary view, showing the tongue locked in an inoperative position.

Referring in detail to the drawings by numerals, 5 designates the body of the alarm which is formed of a single metal plate bent to provide a vertical standard 6, a base flange 7 and a bell supporting plate 8. The base 7 projects from the lower end of the standard 6 at right angles thereto and the plate 8 extends from the top of the central standard 6 in a direction opposite to the base 7, and also at right angles to said standard. The standard 6 of the body and the inner end of the supporting plate 8 are formed with a pair of longitudinal slits and the metal between said slits is bent to provide the spring tongue 9, the upper end of which is turned to form an arm 10. The curved end of said tongue permitting the same to slide upwardly on the door and avoiding the possibility of the tongue being held in an inoperative position due to the biting of the end thereof into the wood of the door.

A bell 11, having a push rod 12 formed with a button 13, is mounted upon the top of the supporting plate 8 and is so constructed as to sound when the rod 12 is pushed inwardly and continue to sound as long as the rod is held in this position and the spring of the bell is under tension. The tongue is sprung so that it normally reposes in the position shown in Fig. 1, and it will be noted that when it is in this position, it is inclined to the plane of the standard 6 and has its arm 10 opposed to the button 13.

A bellerank lever 14 is pivotally secured to the top of the supporting plate 8 by means of the screw 15 and the short arm 16 of the lever forms a hook having the shoulder 17, the curved face 18 and the straight face 19 which intersects the curved face at an angle. A contractile helical spring 20 is secured at one end to the long arm of the lever 14 and at its other end to the supporting plate 8 in such a manner as to throw the hooked arm of the lever against the tongue 9. An angular catch 21 is carried by the tongue 9 and the free extremity of this catch is normally engaged by the curved face 18 of the arm 16.

A brace 22 is pivotally connected at its upper end to the standard at the juncture of the supporting plate 8 and has its lower edge provided with a plurality of floor engaging teeth 23. The brace is connected

to the supporting plate 8 by a pair of angular arms 24 which engage trunnions 25 formed on the edges of the brace adjacent the upper end thereof. This construction 5 permits the brace to swing parallel to the standard 6.

Supplemental to the foregoing description, it is desired to direct attention to the extreme simplicity of the device and the 10 cheapness with which it may be manufactured. The body of the device, the tongue 9, catch 21 and arm 24 may all be formed by properly stamping and bending a flat metal blank. The plate 22, bell 11 and lever 14 15 which are the only other essential features of the device, may be quickly connected to the body, as will be readily apparent.

Having described the construction of my alarm, it now remains to explain briefly the 20 operation thereof: When the device is positioned as shown in Fig. 1, an inward movement of the door will cause the tongue 9 to be forced toward the bell and the arm 10 will engage the button 13 to force the rod 25 12 inwardly and release the bell mechanism. The catch 21 will ride over the curved face 18 of the hooked arm 15 and by engaging the shoulder 17 hold the arm 10 in operative engagement with the button 13, so that the 30 bell will sound as long as the mechanism remains under tension irrespective of whether or not the door is swung away from the tongue 9. If it is desired to use the device merely as a door securer, the tongue 9 35 is sprung outwardly far enough to allow the extremity of the hooked arm 16 to engage the square face 26 of the catch 21 at which time the tongue is locked against movement toward the bell 11.

40 From the foregoing description taken in connection with the accompanying drawings, it will be seen that I have provided a very simple, practical and reliable burglar alarm which will sound when an attempt is 45 made to open a door; which will continue to sound for some time even though the door be quickly closed; and which may be locked so as not to sound when a door is opened, even though the device be in operative position.

While I have shown and described the preferred embodiment of my invention, it will be understood that minor changes in

construction, combination and arrangement of parts may be made without departing 55 from the scope and spirit of the invention as claimed.

Having thus described my invention, I claim:

1. A combined burglar alarm and door 60 stop comprising a base, a standard formed integrally with one end of the base and extending upwardly therefrom, a supporting plate formed integrally with and extending outwardly from the upper edge of the 65 standard, a spring tongue formed on the standard and sprung outwardly therefrom to partially overhang the base, an alarm mounted on the supporting plate to be sounded upon the inward movement of the 70 tongue and a brace pivoted to the supporting plate at the point of juncture with the standard, thereby transmitting any pressure on the standard directly against the brace. 75

2. A burglar alarm and door securer comprising a base, a standard extending upwardly from one edge of the base, the base being adapted to be positioned beneath the bottom of a door, a supporting plate at the 80 upper end of the standard, and extending angularly therefrom in the direction opposite to the base, a spring tongue struck from the standard and bent outwardly in the direction of the base, a bent back arm at the 85 upper end of the tongue and spaced inwardly therefrom for a short distance, an audible alarm mounted on the supporting plate, the alarm being sounded upon the inward movement of the arm into engagement therewith, the outer side of the tongue being positioned against the door beneath 90 which the base is positioned and a brace pivoted to the supporting plate at the point of juncture with the standard whereby pressure transmitted to the standard by the inward movement of the door will be directly transmitted to the brace, thereby preventing the door from being opened, and simultaneously sounding the alarm. 95

In testimony whereof I affix my signature in presence of two witnesses.

ROBERT A. PHILP.
